SELECTIVITY CONTROL FOR RADIO

Leslie F. Curtis, Springfield, Mass., assignor to
United American Bosch Corporation, Springfield, Mass., a corporation of New York

Application September 21, 1934, Serial No. 744,892

REISSUED

18 Claims. (Cl. 250—20)

This invention relates to radio receivers and related equipment and more particularly to superheterodyne receivers in which the overall selectivity may be altered to suit changing requirements. The intermediate frequency amplifier of a superheterodyne usually consists of a number of circuits tuned to a particular frequency and the response curve of the amplifier has its highest point at that frequency. For adjacent frequencies the response is not so great and the curve slopes off on either side. Such a curve would indicate a selective receiver, but one in which tonal quality was sacrificed for selectivity. This condition is known as "side-band cutting" and results in a thin, colorless audio reproduction. Commercial practice has been to compromise these conflicting requirements, and to produce a receiver in which neither the selectivity nor the tone is all that may be desired. The intermediate amplifier was adjusted and remained fixed regardless of insufficient selectivity to separate a weak, distant signal from adjoining signals, and regardless of the full tonal possibilities available in a strong local signal.

The object of this invention is to provide a radio receiver in which the overall selectivity may be varied in accordance with the incoming signal strength.

Another object is to provide radio or related apparatus in which the overall selectivity is automatically controlled in accordance with the incoming signal strength.

A further object is to provide radio apparatus in which an amplifier is adjustable with respect to selectivity by employing either positive or negative feedback.

Still a further object is to provide a radio receiver in which the overall selectivity is controlled through the action of an automatic volume control.

Other objects and advantages will in part be stated and in part be obvious when the following specification is read in connection with the accompanying drawings, in which:

Fig. 1 is a diagrammatic representation of the preferred form of the invention in which a positive feedback is applied to an intermediate frequency amplifier; Fig. 2 is a diagram of an intermediate amplifier in which negative feedback is used to control the selectivity; Fig. 3 is a block diagram of a receiver designed to employ a positive feedback in the intermediate amplifier; and Fig. 4 is a block diagram of a receiver in which a negative feedback is em-

ployed in the intermediate amplifier. Fig. 5 is a diagrammatic representation of an alternative form of the invention in which a positive feedback is applied to an intermediate frequency amplifier.

Figs. 1 and 5 show systems of selectivity control using positive feedback in which inherently broad tuned amplifiers may be made to tune more sharply as requirements change.

Referring to Fig. 1 in more detail, the numeral 1 represents the primary of an intermediate frequency transformer having a secondary 2. A variable condenser 3 tunes the secondary circuit to the desired intermediate frequency of the amplifier. The control grid of an amplifier tube 4 receives the output of the tuned secondary circuit. The tube 4 may be of the type commercially designated as "58" and is connected in a well known manner to function as an amplifier, the particular connections forming no part of this invention. The amplified output of tube 4 passes to a tuned primary circuit comprising the transformer primary 5, tuned by the variable condenser 6. The transformer secondary 7 is likewise tuned by the variable condenser 8. A small condenser 9 is connected between the ungrounded side of secondary circuit 7—8 and the cathode of tube 4. The cathode current of tube 4 is returned to ground through resistance 10, and the voltage drop across resistance 10 provides the necessary minimum bias for the grid of tube 4. The voltage developed across the secondary 1—8 is approximately 90° out of phase with the input voltage supplied by the circuit 2—3. The condenser 9 and the resistance 10 form a phase correction and amplitude adjusting circuit which applies between the cathode of tube 4 and ground a feedback voltage in correct phase which effectively increases the signal voltage between grid and cathode. A supplemental phase correction circuit such as is shown and explained in connection with Fig. 5 may be employed if necessary for correcting minor phase differences due to stray capacities and such. The resistance 11 is the usual filter resistor employed in automatic volume control circuits. A bypass condenser 12 is connected to the low potential side of the secondary circuit 23.

Fig. 2 shows an alternative system of selectivity control in which a sharply tuned amplifier may be broadened for reception of strong signals. The components of the amplifier proper perform the same functions as in the showing of Figs. 1 and 5, and like parts in Figs. 1, 2

and 5 bear the same reference characters. The voltage across the resistance 25 is fed through condenser 27 which forms a portion of a phase correction circuit including resistance 26. From 5 condenser 27 the voltage goes through a coupling condenser 28 to the control grid of the feedback amplifier tube 15. At such times when no automatic volume control bias appears, i. e. when the incoming signal is weak, 10 the tube 15 is given a high negative bias, derived as follows: The automatic volume control bias is applied to the control grid of a relay tube 16. The plate of tube 16 is connected through a resistance 17 to a 90 volt source 15 which is also connected to the cathode of the feedback amplifier tube 15. The tubes 15 and 16 have a minimum bias obtained by the drop across resistances 18 and 19 respectively. A 20 lead including a filter resistance 20 connects the control grid of tube 15 with the plate end of resistance 17. The plate current of tube 16 flows across resistance 17 and the bias on the grid of tube 15 is determined by the resulting voltage drop. When the automatic volume control bias is lowest, the tube 16 has a large plate current and the resulting voltage drop across 25 resistance 17 places a high negative bias on the grid of tube 15, which then passes substantially no feedback voltage. Conversely, when 30 the automatic volume control bias is greatest, tube 16 has very little plate current. The voltage drop across resistance 17 is then practically zero, the added negative bias is removed from tube 15, and there exists maximum amplification 35 of the feedback voltage. Any intermediate automatic volume control bias produces a simultaneous change in the value of the amplified feedback voltage. The output of tube 15 which constitutes the amplifier feedback voltage is connected to a potentiometer 21. A bypass condenser 22 is connected between the supply end 40 of potentiometer 21 and ground. The slider arm of potentiometer 21 takes off any desired portion of the amplified feedback voltage and it is fed through a coupling condenser 23 to the control grid of tube 4. Two feedback amplifier tubes in cascade may be employed in case a greater amplification is desired. The automatic volume control system controls the tube 4 in the usual manner through the lead including the 45 filter resistor 24.

Figs. 3 and 4 are block diagrams of the system which show a positive and a negative feedback respectively in radio receivers.

Fig. 5 shows a modification of the positive feedback system shown in Fig. 1. A resistance 25 is serially included in the circuit 1-8, and has one end grounded. The voltage appearing across resistance 25 is taken off the ungrounded end of the resistance. This voltage will be approximately 90° ahead of the phase of the voltage appearing across the secondary winding 1, and is led to an auxiliary phase correction circuit comprising resistance 26 and condenser 60 27. The auxiliary correction circuit is employed only to compensate for small phase changes due to stray capacities and such incidental circumstances, and under some conditions will not be needed. For incidental phase corrections of 65 opposite sign the positions in the circuit of resistance 26 and condenser 27 will be reversed. A blocking condenser 28 of a value large enough to readily pass the modulated intermediate frequency is connected to the phase shifting circuit, and the control grid of tube 4 is connected 70 75

to the other side of condenser 28. The automatic volume control bias is fed through a resistance 13 of large value which is connected between the control grid of tube 4 and condenser 28. The voltage appearing across the secondary 1 is amplified by the tube 14 and may be passed to a succeeding stage, not shown. 5

High fidelity and extreme selectivity are not compatible. Side band cutting due to extreme selectivity may be reduced by over-coupling the 10 tuned circuits, thereby obtaining a "double peaked" or "flat topped" selectivity curve which is perfectly satisfactory when receiving strong signals. For weak distant stations a much greater selectivity is needed to avoid adjacent 15 channel interference from stronger signals. While this interference may be reduced by employing a tone control to dampen the higher 20 audiofrequencies, the output remains distorted to a large extent. Another remedy has been to 25 vary the selectivity of a receiver through mechanically changing the degree of coupling between tuned circuits by ganging adjustable elements to control the spacing of intermediate amplifier coils. This last method is mechanically cumbersome and prone to get out of adjustment. In the present invention a single 30 manual or automatic adjustment of feedback in an amplifier may be used to control the side band cutting and so control the audio fidelity 35 of a radio receiver. The effect is similar to that obtained by manually adjusting the coupling between intermediate circuits, but without the mechanical complications of this method.

High fidelity response requires that the reproduction from 50 to 7500 cycles per second be uniform within a range of a few decibels. The feedback principle accomplishes this for strong signals, but allows the receiver to function with maximum selectivity on weak signals. 40

If the feedback voltage were introduced directly from the output to the input of a stage, there would be a phase difference of approximately 90° from the proper value. The effect of resistance 25 in series with condenser 8 forms 45 a phase changing circuit as shown in Figs. 2 and 5, which provides the approximately correct phase of feedback, and remains approximately constant over the range of frequencies comprising the side bands of the modulated signal. In 50 actual practice, the effective capacitance of resistors and other units, loses in the coils and shielding, which are not included in the original calculations, may cause a slight additional phase shift, clockwise or counter-clockwise. This may 55 be corrected by a proper selection of resistance 26 and capacitance 21 in the phase correction circuit. Correction for an opposite phase may be made by reversing the relative position of 60 these elements.

For a given selectivity curve, the mathematical product of basic amplification and feedback must remain constant. In an intermediate frequency amplifier having an automatic volume control, the basic amplification without feedback varies with the grid bias of the tubes. For weak signals the greatest selectivity is desired, while strong signals require less selectivity and more fidelity in transmission. This may be accomplished manually by an attenuator in the feedback circuit; however the preferred method is to automatically adjust the feedback to the correct value in proportion to received signal strength as shown in Figs. 1 and 2. 70 75

Positive feedback

The operation of the positive feedback circuit which is shown in Fig. 1 is as follows: The desired feedback voltage in correct amplitude and phase is obtained across resistance 10 by serially connecting the resistance 10 and condenser 9, between ground and the high potential side of the secondary circuit 7-8. This voltage is applied to the cathode of tube 4. The resistance 11 is a filter resistance, serving to keep high frequency voltages out of the balance of the automatic volume control system. The positive feedback is used to make the receiver more selective by symmetrical regeneration. A receiver employing this principle is originally constructed to have a broad selectivity curve, and to amplify the audio side bands of the signal in approximately an equal amount. The receiver will then reproduce with excellent fidelity, but will originally be lacking in selectivity. For a weak signal input, where selectivity is required, the positive feedback in correct phase peaks the selectivity curve by symmetrical regeneration. This peaking effect of a given feedback is greatest when the basic amplification is greatest. In an automatic volume control receiver the amplification is greatest when the signal is weak and thus the feedback is most effective in producing a sharp selectivity curve. Upon the occurrence of a strong signal, the amplification is low, the feedback has little effect on the selectivity, and the curve shape returns to approximately its normal form for the tuned circuit without a feedback. While the feedback may extend over more than one stage of the amplifier, it is then difficult to reinforce the 7000 cycle audio side band when an intermediate frequency of 456 kilocycles is used. Increasing the intermediate frequency sufficiently to accomplish this would probably place it in the broadcast band, and so produce other difficulties. The preferred method of accomplishing the desired result is to provide an individual feedback circuit for each stage as shown in Fig. 3.

Negative feedback

A receiver employing negative feedback to control selectivity, as is shown in Figs. 2 and 4, is originally constructed to have a sharp selectivity curve. Selectivity requisite to separating a weak signal from an adjacent stronger one is originally provided and when a strong station is received and tone becomes the paramount consideration, the selectivity curve is flattened sufficiently to insure substantially equal passage of the audio side bands of the modulated signal. This requires a wide range in the value of the feedback, and a feedback amplifier is provided to allow the desired range. A strong signal requires a heavy negative feedback to sufficiently depress the amplifier selectivity curve, while for a weak signal the feedback should be removed in order to provide maximum selectivity and amplification. As negative feedback of correct phase is increased the amplifier selectivity curve will flatten and then assume the "double hump" characteristic of over-coupled circuits. This may be combined in the usual manner with the characteristic of preceding circuits to produce a flat-topped curve which is wide enough to avoid side band cutting. In this type of receiver, the automatic volume control bias determines the amount of negative feedback at a given time. In the positive feedback system, the

ratio of feedback to signal is constant, and the automatic volume control bias regulates the amplification, which in turn determines the degree of effectiveness of the feedback in altering the selectivity of the amplifier.

It will be apparent that many changes and modifications may be made in this invention by anyone skilled in the art and without departing from the true spirit and scope of the invention as defined in the following claims.

What I claim is:

1. In a radio receiver having an amplifier, a feedback circuit in said amplifier, a relay tube connected to said circuit and controlling said feedback, and means for controlling said relay tube in accordance with signal strength, whereby the selectivity of said amplifier is altered. 15
 2. In a radio receiver having an amplifier, a feedback circuit in said amplifier, phase changing means in said circuit, a relay tube connected 20 to said circuit and controlling said feedback, and means for controlling said relay tube in accordance with signal strength, whereby the selectivity of said amplifier is altered.

3. In a radio receiver, an amplifier having predetermined band-pass characteristics, an electron tube in said amplifier having an input and an output circuit, an energy feedback path from said output to said input circuit, and means including the feedback of energy over said path, 30 whereby the band-pass characteristics of said amplifier may be altered in accordance with the intensity level of substantially any signal capable of affecting said receiver.

4. In a radio receiver, an amplifier having a 35 predetermined selectivity characteristic, an electron tube in said amplifier having an input and an output circuit, an energy feedback path from said output to said input circuit, and means including the feedback of energy over said path, 40 whereby the selectivity of said amplifier is varied inversely with the strength of substantially any signal capable of affecting said receiver.

5. In a radio receiver, an electron tube amplifier having a predetermined selectivity characteristic, an automatic volume control regulating the amplification of said amplifier, said control being operable over substantially the entire range of signal intensities capable of affecting said receiver, a feedback circuit in said amplifier, and a tube in said amplifier receiving both feedback and automatic volume control potential, whereby the selectivity characteristic of said amplifier varies with variations in the amplification thereof.

6. In a radio receiver, an electron tube amplifier having predetermined band-pass characteristics, a volume control in said receiver, and means for imposing a negative feedback potential upon a tube in said amplifier, said means acting jointly with said volume control for altering the band-pass characteristics of said amplifier.

7. In a radio receiver, an electron tube amplifier having predetermined band-pass characteristics, an automatic volume control system, and means for imposing a negative feedback potential upon a tube in said amplifier, said potential varying with different signal intensities, said means acting jointly with said volume control in altering the band-pass characteristics of said amplifier.

8. In a radio receiver, an electron tube amplifier having predetermined band-pass characteristics, an automatic volume control system, and

- means for imposing a negative feedback potential upon a tube in said amplifier, said potential varying with different signal intensities, said means being regulated by said automatic volume control, whereby the band-pass characteristics of said amplifier are altered.
9. In a radio receiver, an amplifier having a predetermined selectivity characteristic, a volume control in said receiver, a feedback circuit in said amplifier, and phase adjusting means in said circuit for imposing a predetermined phase condition upon the energy in said circuit, said volume control and said energy feedback acting jointly to alter the selectivity characteristic of said amplifier.
10. In a radio receiver, an amplifier having a predetermined selectivity characteristic, an automatic volume control in said receiver, a negative feedback circuit in said amplifier, and a phase adjusting means in said circuit for imposing a predetermined phase condition upon the energy in said circuit, said automatic volume control regulating the amount of negative feedback in response to received signal strength whereby the selectivity characteristic of said amplifier is altered.
11. In a radio receiver, an electron tube amplifier having a predetermined selectivity characteristic, an input and an output circuit connected to said amplifier, an energy feedback path from said output to said input circuit, a volume control regulating the amplification of said amplifier, and means including the feedback of energy over said path acting in response to volume control action, whereby the selectivity of said amplifier may be varied in response to substantially all received signal intensities capable of affecting said receiver.
12. In a radio receiver, an electron tube amplifier having a predetermined selectivity characteristic, an input and an output circuit connected to said amplifier, an energy feedback path from said output to said input circuit, means for varying the mutual conductance of said amplifier, and means including the feedback of energy over said path acting in response to variations in mutual conductance, whereby the basic selectivity of said amplifier may be varied in response to substantially all received signal intensities capable of affecting said receiver.
13. In a radio receiver, an electron tube amplifier having a predetermined selectivity characteristic, an input and an output circuit connected to said amplifier, an energy feedback path from said output to said input circuit, a variable grid bias volume control system connected to said amplifier, said control being operative over substantially the entire range of received signal intensities capable of affecting said receiver, and means including a feedback of energy over said
- path acting in response to variations of grid bias to alter the selectivity of said amplifier.
14. In a radio receiver, an electron tube amplifier having a predetermined selectivity characteristic, an input and an output circuit connected to said amplifier, means for producing a feedback of energy from said output to said input circuit, a volume control regulating the output of said receiver, said means acting jointly with said volume control to narrow the selectivity characteristic of said amplifier simultaneously with reductions in received signal intensity over substantially the entire range of said intensities to which said receiver is responsive.
15. In a radio receiver, an electron tube amplifier having a predetermined selectivity characteristic, an input and an output circuit connected to said amplifier, an energy feedback path from said output to said input circuit, a volume control operable over substantially the entire range of received signal intensities capable of affecting said receiver, means for imposing a positive feedback of energy over said path, said feedback energy acting jointly with said volume control to alter the selectivity of said amplifier.
16. In a radio receiver, an electron tube amplifier having a predetermined selectivity characteristic, an input and an output circuit connected to said amplifier, an energy feedback path from said output to said input circuit, a variable grid bias volume control operable over substantially the entire range of received signal intensities capable of affecting said receiver, means for imposing a positive feedback of energy over said path, said feedback energy acting jointly with said volume control to alter the selectivity of said amplifier.
17. In a radio receiver, an electron tube amplifier having a predetermined selectivity characteristic, an input and an output circuit connected to said amplifier, an energy feedback path from said output to said input circuit, a variable grid bias volume control operable over substantially the entire range of received signal intensities capable of affecting said receiver, means for imposing a constant percentage of feedback energy over said path, said feedback energy acting jointly with said volume control to alter the selectivity of said amplifier.
18. In a radio receiver having an amplifier, a feedback circuit in said amplifier, a relay tube connected to said circuit and controlling said feedback, an automatic volume control system in said receiver, and a connection between said system and said relay tube whereby feedback is regulated by the control potentials developed by said systems and the amplifier selectively varied accordingly.

- means for imposing a negative feedback potential upon a tube in said amplifier, said potential varying with different signal intensities, said means being regulated by said automatic volume control, whereby the band-pass characteristics of said amplifier are altered.
9. In a radio receiver, an amplifier having a predetermined selectivity characteristic, a volume control in said receiver, a feedback circuit in said amplifier, and phase adjusting means in said circuit for imposing a predetermined phase condition upon the energy in said circuit, said volume control and said energy feedback acting jointly to alter the selectivity characteristic of said amplifier.
10. In a radio receiver, an amplifier having a predetermined selectivity characteristic, an automatic volume control in said receiver, a negative feedback circuit in said amplifier, and a phase adjusting means in said circuit for imposing a predetermined phase condition upon the energy in said circuit, said automatic volume control regulating the amount of negative feedback in response to received signal strength whereby the selectivity characteristic of said amplifier is altered.
11. In a radio receiver, an electron tube amplifier having a predetermined selectivity characteristic, an input and an output circuit connected to said amplifier, an energy feedback path from said output to said input circuit, a volume control regulating the amplification of said amplifier, and means including the feedback of energy over said path acting in response to volume control action, whereby the selectivity of said amplifier may be varied in response to substantially all received signal intensities capable of affecting said receiver.
12. In a radio receiver, an electron tube amplifier having a predetermined selectivity characteristic, an input and an output circuit connected to said amplifier, an energy feedback path from said output to said input circuit, means for varying the mutual conductance of said amplifier, and means including the feedback of energy over said path acting in response to variations in mutual conductance, whereby the basic selectivity of said amplifier may be varied in response to substantially all received signal intensities capable of affecting said receiver.
13. In a radio receiver, an electron tube amplifier having a predetermined selectivity characteristic, an input and an output circuit connected to said amplifier, an energy feedback path from said output to said input circuit, a variable grid bias volume control system connected to said amplifier, said control being operative over substantially the entire range of received signal intensities capable of affecting said receiver, and means including a feedback of energy over said
- path acting in response to variations of grid bias to alter the selectivity of said amplifier.
14. In a radio receiver, an electron tube amplifier having a predetermined selectivity characteristic, an input and an output circuit connected to said amplifier, means for producing a feedback of energy from said output to said input circuit, a volume control regulating the output of said receiver, said means acting jointly with said volume control to narrow the selectivity characteristic of said amplifier simultaneously with reductions in received signal intensity over substantially the entire range of said intensities to which said receiver is responsive.
15. In a radio receiver, an electron tube amplifier having a predetermined selectivity characteristic, an input and an output circuit connected to said amplifier, an energy feedback path from said output to said input circuit, a volume control operable over substantially the entire range of received signal intensities capable of affecting said receiver, means for imposing a positive feedback of energy over said path, said feedback energy acting jointly with said volume control to alter the selectivity of said amplifier.
16. In a radio receiver, an electron tube amplifier having a predetermined selectivity characteristic, an input and an output circuit connected to said amplifier, an energy feedback path from said output to said input circuit, a variable grid bias volume control operable over substantially the entire range of received signal intensities capable of affecting said receiver, means for imposing a positive feedback of energy over said path, said feedback energy acting jointly with said volume control to alter the selectivity of said amplifier.
17. In a radio receiver, an electron tube amplifier having a predetermined selectivity characteristic, an input and an output circuit connected to said amplifier, an energy feedback path from said output to said input circuit, a variable grid bias volume control operable over substantially the entire range of received signal intensities capable of affecting said receiver, means for imposing a constant percentage of feedback energy over said path, said feedback energy acting jointly with said volume control to alter the selectivity of said amplifier.
18. In a radio receiver having an amplifier, a feedback circuit in said amplifier, a relay tube connected to said circuit and controlling said feedback, an automatic volume control system in said receiver, and a connection between said system and said relay tube whereby feedback is regulated by the control potentials developed by said systems and the amplifier selectively varied accordingly.
